ELECTRIC IRON CORD HOLDER

Filed June 8, 1925

20 25 Inventor
William G. Aufenast

By H. Maedick

Attorney

UNITED STATES PATENT OFFICE.

WILLIAM G. AUFENAST, OF ST. PAUL, MINNESOTA.

ELECTRIC-IRON CORD HOLDER.

Application filed June 8, 1925. Serial No. 35,601.

My invention relates to electric iron cord holder wherein it is desired to provide a holder for the surplus cord of the iron to support the cord extending upward from the iron over to the socket and to provide holding means which is adapted to compensate readily as the iron is moved back and forth into different positions over the ironing board.

10 A feature of my invention resides in means adapted to provide a cord engaging member which extends normally in an upright position and which is hingedly supported in a manner so that it can swing downward from 15 the upright position. Suitable spring means is provided which holds the arm normally erect and which permits the arm to move downward to compensate for the movement of the iron so that the electric cord connecting the iron is not in the way during 20 the operation of the iron.

It is also a feature of my invention to provide a bracket which is removably held to a wall plate. The bracket is adapted to 25 support the electric cord holding arm pivotally and carries the spring means which holds the cord arm in erect position normally, while the bracket is provided with a cord arm supporting member which is pivotally connected to the main bracket which is 30 removably held as a unit from the wall supporting plate. This construction provides an electric cord holder which is adapted to compensate for the lengthening of the 35 cord to permit the same to straighten out to the position desired and also permits the swinging of the cord supporting arm in a horizontal plane so that the electric cord is held in a most practical manner freely to 40 move back and forth and to lengthen out while the iron is being used.

With my electric iron cord holder I provide a supporting means which is very desirable as it holds the cord of the iron up away 45 from the same and this is quite an important feature as it prevents the cord from being entangled with the clothes that are being ironed and also prevents the cord from coming into contact with the hot iron which 50 is very detrimental to the insulating material covering the iron cord. My iron cord holder is designed to hold the cord in the most convenient manner while the iron is being used.

55 My cord holder and support is designed

to operate equally well with either an electric cord or the gas pipe cord which is used for gas irons, so that the hose extending from the gas jet to the iron may be supported to hold the same up away from the ironing board and the iron, and I have found that my holder provides a very practical means of supporting the gas hose to prevent injury to the same from the hot iron and to hold the surplus hose up out of 60 the way of the operator in using the iron, yet freely movable into any desired position in operation.

These features together with other objects of my invention will be more fully set forth 70 in the following specification and claims.

In the drawings forming a part of my specification:

Figure 1 is a perspective view of my electrical iron cord holder, a portion of which 75 is broken away and illustrating the holder as it would appear in use, only a portion of the electrical cord being illustrated.

Figure 2 is a side view of a portion of my cord holder, a part of which is broken away 80 and the pivoted cord arm supporting member being illustrated in a position turned to one side.

Figure 3 is a plan view of Figure 2, illustrating in dotted outline the pivotal position 85 of the bracket of the support in relation to the cord supporting member.

Figure 4 is a front view of the wall plate.

Figure 5 is a top, edge view of the wall plate. 90

Figure 6 is a front view of a different form of wall plate, associated with an electrical switch plate.

Figure 7 is an upper edge view of the plate illustrated in Figure 6. 95

In the drawings I have illustrated my electric cord holder A as it would appear in use, in Figure 1, adapted to support the electric cord B, only a portion of which is illustrated in the drawings.

The holder A is formed with a bracket 10 which is formed from a single piece of sheet material and is provided with a horizontally extending upper lip 11 and a horizontally extending lower lip 12. The lips 11 and 12 extend from the back portion 13 and approximately at right angles thereto so that the back 13 constitutes the portion of the bracket 10 which holds the lips 11 and 12 spaced apart. The back portion 13 is of a 105 110

comparatively long flat strip to provide a bearing surface for the back of the bracket 10.

Extending integral from the lip 11 I provide a downwardly extending tongue 14 which is positioned approximately parallel to the back 13. The tongue 14 is adapted to engage back of the upper portion 21 of the wall plate 16. The lower portion 15 of the plate 16 is provided with channel shaped reinforcing ribs 17 on either side of the same which project forwardly from the portion 15 and provide a recess between which the lower end of the back 13 extends 16 to hold the same firmly against side movement when the tongue 14 is engaging back of the portion 21 of the plate 16.

The plate 16 is provided with wall engaging flanges 18 extending longitudinally along 20 the side of the same which are bent to be offset from the central body portion 19 of the plate so as to space the central portion 19 away from the wall when the flanges 18 are secured to the same. This provides a 25 spacing to permit the free engagement of the tongue 14 back of the body portion 19 from which the portion 21 extends at the upper end of the plate 16. The flanges 18 are provided with openings 20 adapted to receive 30 screws or other suitable means to attach the plate 16 to the wall.

Pivots connected to the outwardly extending lips 11 and 12 I provide a member 22 which is pivoted at 23 to the lips 11 and 35 12 and which is provided with channel shaped body portion with outwardly projecting longitudinally extending side flanges 24 which are adapted to strengthen the member 22 and to provide a longitudinally extending recess of approximately channel 40 shape to receive the electric cord supporting arm 25.

The arm 25 is formed of a single piece of wire which is bent in a manner so that the 45 ends of the same are adapted to extend through the flanges 24 near the lower end of the flanges to pivotally connect the arm 25 at 26 to the member 22. In attaching the arm 25 at the pivotal points 26 I provide 50 a plate member 27 which is adapted to space the ends of the arm 25 apart to hold the same in pivotal connection with points 26 with the member 22. In assembling the arm 25 with the member 22 the plate member 27 55 is positioned near the top of the arm to permit the ends of the arm to be squeezed together sufficiently so that the ends are engaged in the openings in the flanges 24 to 60 pivotally connect the same at 26. When the ends are in the openings I slide the plate 27 down to the position illustrated in Figure 1. The plate 27 is formed with longitudinally extending side edges 28 of a tubular nature so as to slide under frictional tension 65 on the sides of the arm 25. When the

plate 27 is moved down into the position illustrated in Figure 1 the frictional contact of the tubular portions 28 is sufficient against the arms 25 to hold the plate in position. Should it be desired to remove the 70 arm 25 from the member 22 this can be done by sliding the plate 27 towards the upper free end 25.

The member 22 is provided with a longitudinally extending opening 29 in the back 75 of the same through which the coil spring 30 extends. One end of the coil spring 30 is secured to the downwardly depending tongue 31 which is formed integral with the upper end of the member 22 while the other end of the coil spring 30 is connected through the openings 32 to the plate 27. The coil spring 30 is adapted to hold the arm 25 in erect position normally so that the lower pivoted end of the arm 25 will extend in 80 the channel shaped recess of the member 22 as illustrated in Figure 3 of the drawings. The spring 30 is illustrated in Figure 1 partly extended so that the arm 25 is extending out of the channel recess between 85 the flanges 24 as it would appear in use with the weight of the cord B held by the upper free end of the arm.

The upper end of the arm 25 is bent to 90 form a pair of oppositely extending loop recesses 35 and 36 which are adapted to be of any suitable shape so as to receive the cord B to hold the same in engagement with the free end firmly against slipping under ordinary 95 conditions in the loops. In fact the cord can be threaded back and forth through the loops. It is obvious that the shape of the loops can be varied to engage a gas pipe 100 hose for gas irons so as to readily support the hose as it is desired, or cord, can be threaded through the loops which is adapted to engage the gas pipe hose and support the same between the free ends of the gas 105 hose or pipe.

The arm 25 engages the cord B between the 110 ends at that portion which would ordinarily drag upon the floor and be in the way of the housewife using the iron.

The arm 25 is held in upright position by the coil spring 30 which is of any suitable 115 tension to properly support the iron 25 and by engaging with the cord B or with a gas pipe hose, not illustrated in the drawings, the arm is held supported so that the surplus portion of the same will not drag on the floor and will be free to move back and forth or rotate about the pivotal connections 23 which permit the arm 25 to rotate about the bracket 10 which is firmly and rigidly supported on the wall plate 16. This permits the electrical cord B to swing back and forth and to lengthen out in a very desirable manner, yet holding the same up out of the way and I have found in actual use that my cord 120 holder is practical, and I believe, from my 125 130

personal experience, will fulfill a long felt want in household utilities in providing a very effective device for holding the electric cord.

5 When the holder A is not desired for use it can be readily disengaged from the wall plate 16 by lifting upwardly on the same which disengages the tongue from the back of the portion 21 of the plate 16. The holder 10 can then be laid aside until it is again wanted for use, however it is also practical to leave my holder directly attached to the wall, as the coil spring holds the arm practically erect out of the way, and when my holder 15 is finished in a lacquer or plated finish it provides a holder of an attractive nature forming a part of the wall fixtures associated with the plate for the electric iron or the gas jet as may be the case in the home where 20 it is used.

A different form of my wall bracket is illustrated in Figure 6 wherein the wall plate 40 is formed as an integral part with the plate portion 41 which forms the front 25 plate of the electrical connection 42 for the cord of the electric iron. In the plate 41 is the ordinary glass closure 43 for the pilot light back of the plate 41 and switch buttons 44 which may be of any suitable construction. In furnishing my cord holders as 30 standard equipment for electric fixtures it is quite desirable to make the plate 40 integral with the plate 41, as illustrated in Figures 6 and 7 of the drawings.

35 In accordance with the patent statutes I have described the principles of operation of my cord holder together with the best embodiment thereof, and while I have illustrated a particular formation of the same 40 in the drawings, I desire to have it understood that this is only suggestive and that the invention can be carried out by other means, and applied to uses other than those above set forth within the scope of the following claims.

I claim:

1. A cord holder including a bracket member, a wall plate adapted to detachably support said bracket member, an arm supporting member having a channel shaped body portion, means for pivotally connecting said arm supporting member to said bracket member, a cord holding arm pivotally connected to said arm supporting member and a spring connected to said arm and said arm supporting member to hold said arm normally in an erect position.

2. An electric ironing cord supporting device including an arm having cord engaging means formed on one end, a member adapted to pivotally support the other end of said arm, side flanges formed on said member adapted to support said arm, a plate member adapted to engage the pivotal ends of said arm in a manner to hold the same spaced apart and into pivotal engagement with said arm supporting member, a coil spring adapted to engage said plate on one end and supported to said arm supporting member on the other end and bracket means adapted to pivotally support said arm supporting member in a manner to permit the same to swing in a horizontal plane whereby said cord supporting device is adapted to hold the slack part of the cord up out of the way in ironing.

3. A cord supporting device adapted to be associated with an electric iron and cord, a wall plate member, a bracket removably supported by said wall plate, a member pivotally supported to said bracket in a manner to swing in a horizontal plane, a cord supporting arm pivotally connected to said horizontally moveable member and spring means connected with said arm and said horizontally moveable member adapted to hold the free end of said arm in upright position to hold the slack of the ironing cord out of the way of the operator in using the iron.

WILLIAM G. AUFENAST.
